METHOD FOR ATTACHING MEMBERS BY
VACUUM PRESSURE

Laurence W. Van Dusen, San Diego, Calif., assignor to Van Dusen Engineering Company, San Diego, Calif., a copartnership

Application March 6, 1948, Serial No. 13,368

4 Claims. (Cl. 29—148.2)

1

This invention relates to the use of vacuum pressure for securing members in assembled relation. This invention finds usefulness in a number of different fields and is particularly useful in connection with vacuum insulated containers and in securing together structural units composed of glass, tile, ceramics, and vitreous products generally, as well as plastic materials and metallic materials.

An important object of this invention is to provide a new and improved method for securing together structural or other members by vacuum pressure.

Another object is to provide new and improved forms of vacuum insulated containers.

A further object is to provide a novel form of resilient sealing ring adapted to be confined between members secured in assembled relation by suction pressure.

A more detailed object is to provide an improved sealing ring and mounting therefor for attaching a plurality of members forming a composite container in assembled relation by means of suction pressure.

Other objects and advantages will appear hereinafter.

In the drawings:

Figure 1 is a side elevation partly in section showing a vacuum insulated container embodying my invention.

Figure 2 is a sectional plan view taken substantially on the line 2—2, as shown in Figure 1.

Figure 3 is a sectional detail partly broken away showing the method of withdrawing air from space between nesting container shells in accordance with my invention, and also illustrating a preferred type of resilient seal ring.

Figure 4 is a view similar to Figure 3 illustrating the container parts as held in assembled relation by vacuum pressure.

Figure 5 is a side elevation partly in section showing a modified form of vacuum insulated container such as, for example, a coffee pot.

Figure 6 is a sectional detail of the seal ring and mounting employed in connection with the device shown in Figure 5, prior to extraction of air between the container shells.

Figure 7 is a view similar to Figure 6 showing the parts in assembled relation under vacuum pressure.

Figure 8 is a perspective view of an item of household furniture having various component parts maintained in assembled relation by means of the process and apparatus embodying my invention.

2

Figure 9 is a sectional view partly broken away taken substantially on the lines 9—9, as shown in Figure 8.

Figure 10 is a side elevation partly in section showing a further modified form of vacuum insulated container embodying my invention.

Figure 11 is a sectional detail partly broken away showing on an enlarged scale the sealing ring and associated parts used in connection with the device illustrated in Figure 10.

Figure 12 is a partial perspective view showing details of the hinge construction of the device shown in Figure 10.

Figure 13 is a sectional elevation showing the application of my invention to a skylight construction.

Referring to the drawings, the ice bucket shown in Figures 1 to 4 illustrates a preferred embodiment of my invention. The parts of the device 20 may be formed of any suitable or desirable materials, but I have chosen to illustrate the broad principles of my invention in connection with materials such as glass, tile, and other vitreous substances. Accordingly, the outer shell 10 and the inner shell 11 may be constructed of glass. The inner shell 11 is adapted to fit within the outer shell 10 and to define a clearance space or chamber 12 therebetween. The inner shell 11 is provided with an outwardly extending lip 13 which may extend into a recess 14 provided in the upper portion of the outer shell 10. Parallel shoulders or radial surfaces 15 and 16 on the inner and outer shells respectively cooperate with the shells to define a cavity 17 which encircles the inner shell 11. As shown in the drawings, the shells are circular in cross-section, and accordingly the cavity 17 is annular in shape.

Means are provided for sealing the clearance space 12 and for evacuating the air therefrom in order to hold the shells 10 and 11 in assembled relation and to provide an insulation jacket for the inner shell 11. As shown in the drawings, this means includes a resilient sealing ring 18 mounted within the annular cavity 17 and adapted to contact the juxtaposed shoulders 15 and 16. A port comprising a lateral opening 19 is provided in the upper portion of the outer shell 10, and a hollow needle 20 is adapted to be inserted through the port 19 to pierce the central body portion of the sealing ring 18. A flexible hose 21 is connected to the hollow needle 20 and to a device 22 for applying suction pressure to the hose 21 and needle 20. The device 22 may include a vacuum pressure gage 23 and a valve 24 leading to a line 25 connected to a source of

vacuum pressure. Accordingly, when the valve 24 is opened, suction in the hose 25 and needle 26 serves to evacuate the space 12 between the inner and outer shells and thereby compress the resilient rubber-like sealing ring 18. The ring 18 then may take the shape illustrated in Figure 4.

While it is recognized that rings of conventional circular cross-section may be employed in connection with my invention, I prefer to use rings having a noncircular cross-section such as, for example, as shown in Figures 3, 6 and 9. Each of these forms of sealing rings has a central body section and a plurality of outwardly extending lips which initially contact the adjacent shoulders 15 and 16.

The construction is such that the lips form an adequate seal to permit evacuation of the space 12 to proceed, and after a pressure differential is established between the space 12 and the interior of the shell 11 the sealing ring is distorted sufficiently to bring the central body portion into contact with the shoulders 15 and 16. As shown in Figure 3, the lips 26 initially contact the shoulders 15 and 16, and a relatively light endwise force is sufficient to effect an initial seal. When a large pressure differential is established between the space 12 and the interior of the shell 11, the ring is distorted as shown in Figure 4. This feature has been found to be highly advantageous, since the space between the shoulders 15 and 16 may not be absolutely uniform, particularly if glass is employed as the material for the shells, and hence the provision of the lips 26 enables an initial seal to be effected between the shells even though some irregularity of the surfaces 15 and 16 exists.

When the space 12 has been evacuated to the desired degree, the hollow needle 20 is simply withdrawn through the opening 19. The pierced hole in the rubber-like ring 18 promptly seals itself under the force exerted by the pressure differential. It will be observed that a relatively small difference in pressure will produce a relatively large force, because the mounting of the ring is such that the full effective end area of the inner shell including the lip 13 is available to atmospheric pressure. Accordingly, the unit pressure on the rubber ring is relatively high, and an effective seal of the puncture is easily maintained.

For example, it may be shown that the pressure tending to seal the ring against the flanges is equal to $\pi \cdot r^2 \cdot P$, where r is the mean radius of a circular rubber washer and P is the atmospheric pressure. The area of the rubber on which this pressure is acting is equal to $\pi \cdot d \cdot w$, where d is the diameter of the circular rubber washer and w is the width across a section of the washer. The total pressure U in p. s. i. tending to seal the rubber washer equals the total pressure acting divided by the area of the rubber on which this pressure is acting.

$$\text{Hence } U = \frac{\pi \cdot r^2 \cdot P}{\pi \cdot d \cdot w}$$

Since $d = 2r$, the total pressure acting on the rubber ring equals

$$\frac{rP}{2w}$$

On an 8" diameter circle using a rubber ring $\frac{1}{8}$ " in width across a section, the total sealing pressure is approximately 240 p. s. i., the unit

pressure tending to cause the leak to be atmospheric, or approximately 15 p. s. i. Accordingly, an effective sealing action is accomplished.

The inner surface 27 of the outer shell 10 may be silvered prior to assembly with the inner shell 11. This silvering not only lends an attractive appearance to the device but is effective in reflecting a major portion of radiant energy which might otherwise be transmitted through the shells to heat the contents of the inner shell 11. Since the silvering operation can be accomplished before assembly of the shells, it is possible to effect substantial manufacturing economies in applying the silver coating to the inner surface of the shell 10.

A lid 28 of any suitable or desirable shape may be provided to close the opening in the upper end of the inner shell 11. This lid 28 may rest on the upper surface 29 of the lip 13. The vacuum insulated container provided by the nesting shells 10 and 11 may be used for any suitable or desirable purpose such as, for example, as a container for cracked ice or ice cubes. By suitably proportioning the inner and outer shells a vacuum insulated drinking glass may be provided. It will be understood that the lid 28 may be omitted if desired.

In Figures 5, 6 and 7 I have shown details of coffee making apparatus which may employ essential features of my invention. Inner and outer nesting shells 30 and 31 respectively are provided, and these shells define a clearance space 32 therebetween. The shells may be formed of glass or any other suitable material. An annular cavity 33 is formed between shoulders 34 and 35, and a resilient rubber-like sealing ring 36 is positioned in the cavity. Lips 37 on the ring contact the shoulders initially, and upon insertion of the hollow needle 20 through the port 37a and through the body of the ring 36 the space 32 may be partially evacuated to compress the ring 36 to the distorted shape illustrated in Figure 7. Upon withdrawal of the hollow needle 20 the end pressure between the shoulders 34 and 35 seals the puncture in the ring and permits no leakage whatever. To this extent the device shown in Figure 5 is similar to that described in connection with Figures 1 to 4 above.

A basket-type insert generally designated 38 may be positioned within the inner shell 31. This insert may be of conventional style and includes a circular perforated container 39 mounted on tube 40 and provided with a flanged base 41. Ground coffee placed in the container 38 is subjected to so-called percolator action when the fluid within the inner shell 31 is heated. The lid 42 may include the usual sight indicator 43 for observing the percolating action. The lid 42 may rest on the upper surface of the shell 31, or if desired may be pivotally mounted on the outer shell in any convenient fashion. A suitable form of handle 50 may be attached to the outer shell as shown.

In order to heat the contents of the inner shell 31, I prefer to provide a heat lamp 44 adapted to direct radiant energy through the bottom 45 of the outer shell 30 across the space 32 and through the bottom 46 of the inner shell 31. The surface of the bottom 46 may be coated with black paint or other heat absorbing medium 47. This coating may be applied before the inner shell 31 is placed in assembled relation within the outer shell 30. If desired, the lamp 44 may be enclosed within a reflector casing 48 which is adapted to support the outer shell 30. Electric energy for

the lamp 44 may be provided through the lead wires 49.

After the coffee making cycle has been completed, the lamp may be extinguished and the insert unit 38 and contents withdrawn from the interior of the shell 31. The coffee pot unit generally designated 51 and including the inner and outer shells and lid 42 then may be carried from place to place by means of the handle 50. The coffee stays hot because of the insulating character of the evacuated space 32.

As shown in Figures 8 and 9, the method and apparatus pertaining to my invention may be advantageously used in the assembly of structural units. The coffee table generally designated 60 may include a slab 61 which serves as the upper surface of the table. This slab may be formed of a laminated plastic material such as, for example, Bakelite, or if desired may be formed of glass or other vitreous product. The legs of the table may be conveniently formed of commercially available glass building blocks 62 and 63. Assembly of blocks 62 and 63 and slab 61 is readily accomplished by providing a rubber-like resilient gasket or sealing ring 64 between adjacent ends of the blocks and between the blocks 62 and the slab 61. Evacuation of the air between the blocks then results in a permanent assembly held together by suction pressure.

The evacuation may be conveniently effected by means of the hollow needle 20 and associated parts shown in Figure 3. The needle is inserted through the central body portion of the seal ring 64 between the outwardly extending lips 65. When the air pressure between the glass blocks has been reduced sufficiently the needle 20 is simply withdrawn. The effective end area of the block is sufficiently large in relation to the size of the seal ring 64 to develop a relatively large squeezing force on the ring, and the puncture in the ring is thus effectively sealed. The cross-section of the ring 64 differs from those shown in Figures 3 and 6, but it will be understood that any of these types may be used. The outwardly extending sealing lips 65 afford an initial seal even though the adjacent surfaces of the blocks may not be uniformly spaced.

It will thus be understood that by means of the advantages flowing from my invention the various structural elements of the table 60 may be secured together without requiring unsightly bolts, screws, or attachment fittings, and no attachment holes need be drilled or otherwise provided.

The vacuum insulated container shown in Figures 10, 11 and 12 employs a U shaped annular sealing ring 70. This ring has an upper lip 71 adapted to seal against the outwardly directed flange 72 on the upper end of the inner shell 73. The lower lip 74 seals against the inwardly directed flange 75 on the upper end of the outer shell 76. The space between the lips 71 and 74 receives an inwardly directed ledge 77 provided on the rim member 78. The arrangement of the flanges 72 and 75 and the ledge 77 is such that the single rubber-like ring 70 is enabled to hold the rim member 78 and inner and outer shells 73 and 76 in assembled relation.

Evacuation of the space 79 between the shells 73 and 76 is accomplished by inserting the hollow needle 20 into the aperture 80 and through the lower lip 74. When the air pressure has been lowered sufficiently within the space 79, the needle 20 is withdrawn. The relatively large squeezing force produced by atmospheric pres-

sure acting over the maximum diameter of the inner shell 73 then acts to seal effectively the puncture left by the hollow needle 20. An important feature of this construction is that the rim member 78 and ledge 77 may be formed of somewhat porous material without affecting the air-tight seal between the shells 73 and 76. Thus the rim member and ledge may be formed as a metallic die casting, if desired, and any possible porosity would have no bad effects.

The rim member 78 may be provided with a plurality of laterally extending fingers 81 carrying a hinge pin 82 near their outer ends. A cover assembly generally designated 83 is mounted on the hinge pin 82, and this assembly includes a closure 84 adapted to seat on the upper portion of the rim member 78. A forwardly extending handle 85 is provided for raising and lowering the closure 84 about the hinge pin 82. A pair of crusher jaws 86 may be carried on the assembly 83 and adapted to enter the spaces between the fingers 81. The jaws 86 and fingers 81 thus cooperate to provide an effective device for crushing ice cubes. The ice cubes may be stored within the vacuum insulated container and withdrawn for crushing as needed. It will be noted that when the closure 84 is in closed position the jaws 85 extend completely through the spaces between the fingers 81, and hence all of the crushed ice is ejected when the handle 85 is lowered.

The skylight construction shown in Figure 13 illustrates another use of the method and apparatus embodying my invention. Glass plates 91 and 92 are held in assembled relation by means of a partial vacuum in the space 93 between them. The plates are separated by a sealing ring 94 which may be U-shaped in cross-section to receive an inwardly protruding ledge 95. The ledge 95 may form part of the structural framework of the building, and any porosity of the material from which the ledge is constructed does not affect the air-tight seal between the plates 91 and 92. The space 93 is evacuated by means of a hollow needle in the manner described above in connection with Figure 11. A relatively simple yet effective mounting for a weatherproof skylight is thus provided without requiring the use of conventional attachment fittings.

Other uses for my improved method of attaching members by vacuum pressure are also contemplated. Thus, for example, a towel rack may be rigidly attached to a tile, porcelain or enamelled surface without the necessity of drilling holes for attachment bolts or fittings. Also fixtures may be attached to glass or brick walls and the mounting of mirrors may be simplified by means of my invention. Mounting office equipment on metal filing cabinets, the assembly of plastic glass or metal lamp bases, assembly of moisture-proof dust-tight display cases are other illustrations of the application of the essential features of my invention. The attachment achieved is permanent in character, since synthetic rubber-like materials, such as for example neoprene, are available which show little if any deterioration upon long exposure to air at ordinary temperatures. Such materials effectively withstand temperatures as high as that of boiling water, and hence the seal rings illustrated in connection with the coffee maker in Fig. 5 and skylight in Figure 13 have practically indefinite length of service life.

The source of suction pressure for the hollow needle 20 may be a suction pump, either power

driven or manually operated. In many cases suction pressure developed by the mouth of the operator may be adequate. Suction may also be generated by the action of a venturi. The needle itself may take that form of a commercially available hypodermic needle, and hence is of such small diameter as to leave a puncture of minimum size.

Having fully described my invention, it is to be understood that I do not wish to be limited to the details herein set forth, but my invention is of the full scope of the appended claims.

What is claimed is:

1. The method of securing together inner and outer nesting shells of a double wall container, comprising the steps of providing a counterbore within the wall at the mouth of the outer shell, said counterbore having a radial surface, forming an aperture in said wall communicating with the counterbore, providing a peripheral lip on the wall at the mouth of the inner shell so that the lip may be received within the counterbore, said lip having a radial surface, inserting a distortable rubber-like sealing ring in the counterbore between said radial surfaces on said wall and said lip, holding said radial surfaces in contact with said sealing ring to form an initial seal therebetween, projecting a hollow needle laterally through said aperture and through the sealing ring to puncture said sealing ring and establish communication with the space between said nesting shells, applying suction pressure to said hollow needle to evacuate said space, and withdrawing the needle laterally through the aperture to permit the longitudinal squeezing force on the sealing ring developed by atmospheric pressure acting upon the exterior of the shells to seal the needle puncture in the sealing ring and to prevent disassembly of the shells.

2. The method of securing together inner and outer nesting shells of a double wall container, the outer shell having an axially extending wall with a radial surface defining an annular recess for reception of a peripheral lip on the inner container, said lip having a radial surface, and the wall having an aperture extending therethrough and communicating with said recess, the steps comprising: inserting a distortable rubber-like sealing ring in the recess between said radial surfaces on said wall and said lip, holding said radial surfaces in contact with said sealing ring to form an initial seal therebetween, projecting a hollow needle laterally through said aperture and through the sealing ring to puncture said sealing ring and establish communication with the space between said nesting shells, applying suction pressure to said hollow needle to evacuate said space, and withdrawing the needle laterally through the aperture to permit the longitudinal squeezing force on the sealing ring developed by atmospheric pressure acting upon the exterior of the shells to seal the needle puncture in the sealing ring and to prevent disassembly of the shells.

3. The method of securing together inner and outer non-porous nesting shells of a double wall container together with a separate porous rim member on the outer shell, comprising the steps of providing inwardly directed flanges on the outer shell and rim member and an outwardly directed flange on the inner shell, inserting a

distortable gasket U-shaped in cross-section so that the flange on the rim member is received between the legs of the U and so that the shell flanges engage above and below the gasket, holding the flanges in contact with the gasket to form an initial seal therebetween, projecting a hollow needle laterally through one leg of said gasket to puncture the gasket and establish communication with the space between said nesting shells, applying suction pressure to said hollow needle to evacuate said space, and withdrawing the needle laterally to permit the longitudinal squeezing force on the gasket developed by atmospheric pressure acting upon the exterior of the shells to seal the needle puncture in the gasket and to prevent disassembly of the shells and rim member.

4. The method of securing together inner and outer non-porous nesting shells of a double wall container together with a separate porous rim member on the outer shell, comprising the steps of providing inwardly directed flanges on the outer shell and rim member and an outwardly directed flange on the inner shell, inserting a distortable gasket U-shaped in cross-section so that the flange on the rim member is received between the legs of the U and so that the shell flanges engage above and below the gasket, said rim having an aperture in the same plane as one leg of the gasket, holding the flanges in contact with the gasket to form an initial seal therebetween, projecting a hollow needle laterally through the aperture in the rim and through one leg of said gasket to puncture said gasket and establish communication with the space between said nesting shells, applying suction pressure to said hollow needle to evacuate said space, and withdrawing the needle laterally to permit the longitudinal squeezing force on the gasket developed by atmospheric pressure acting upon the exterior of the shells to seal the needle puncture in the gasket and to prevent disassembly of the shells and rim member.
